UNITED STATES PATENT OFFICE.

BENNETT E. JORDAN, OF HUGO, OKLAHOMA, ASSIGNOR OF ONE-HALF TO R. D. WILBOR,
OF HUGO, OKLAHOMA.

REIN-SPUR.

1,218,088.

Specification of Letters Patent.

Patented Mar. 6, 1917.

Application filed December 20, 1916. Serial No. 138,084.

To all whom it may concern:

Be it known that I, BENNETT E. JORDAN, a citizen of the United States, residing at Hugo, in the county of Choctaw and State of Oklahoma, have invented certain new and useful Improvements in Rein-Spurs, of which the following is a specification, reference being had to the accompanying drawings.

10 This invention relates to an improved rein spur and has for its primary object to provide a simply constructed and effective device which can be easily and quickly applied to one of the reins or lines, whereby the 15 horse or other animal may be spurred or goaded into renewed activity.

It is another and more particular object of the invention to provide a device for the above purpose, consisting of a circular, metal 20 disk having a toothed or serrated perimeter and a central, elongated opening therein, and spaced plates secured to the opposite edges of said opening and between which the rein or line is adapted to be disposed, said plates 25 having clamping pressure upon opposite sides of the rein.

It is a further general object of my invention to provide a rein spur which is durable in its construction, may be manufactured at small cost, and is highly convenient 30 and serviceable in practical use.

With the above and other objects in view, my invention consists in the novel features 35 of construction, combination and arrangement of parts to be hereinafter more fully described, claimed and illustrated in the accompanying drawing, in which,

Figure 1 is a perspective view showing my improved spur applied to a rein;

40 Fig. 2 is a longitudinal section; and

Fig. 3 is a section taken on the line 3—3 of Fig. 2.

Referring in detail to the drawing, 5 designates a metal plate or disk of circular 45 form and preferably of sheet steel. The perimeter of this disk is toothed or serrated as indicated at 6, and said disk is also provided with a diametrically extending, elongated slot 7 therein.

50 To the opposite longitudinal edges of the slot 7, the rectangular, metal plates 8 are centrally soldered or otherwise securely fixed, said plates extending in spaced, parallel relation beyond the opposite side faces 55 of the disk.

In the application of the device to the rein R, the rein is inserted between the plates 8 at one of their ends and drawn through the opening 7 in the disk 5. The end portions of the plates 8 exert a sufficient resilient 60 clamping pressure upon the sides of the rein to retain the spur in the desired position upon the rein. The spur may, therefore, be easily and quickly adjusted so that it will 65 strike the hide of the animal at the desired place, and may also be readily removed from the rein or replaced thereon. Such a device is particularly desirable for use when driving two or more horses or other draft animals, the spurs being applied to the proper 70 rein so that the animal which shirks or lags may be spurred and thereby caused to assume its portion of the draft. The points or teeth on the plate 5 may be dulled or sharpened, as may be required, by the use of 75 a suitable file.

From the foregoing description, taken in connection with the accompanying drawing, the construction, manner of use and several 80 advantages of the device will be clearly and fully understood. While I have herein referred to a circular toothed plate 5, it will be understood that this plate may be of various other forms if desired, and the clamping plates 8 engaging the rein may also be of 85 any desired length. The device is also susceptible of other modifications in the form, proportion and arrangement of its several features and it will, therefore, be understood 90 that I reserve the privilege of adopting all such legitimate changes as may be fairly embodied within the spirit and scope of the invention as claimed.

Having thus fully described my invention, what I desire to claim and secure by Letters Patent is:—

1. A device of the character described comprising a plate having a toothed outer edge and a central opening therein to receive a rein, and clamping means projecting from the opposite side faces of the plate at right angles to the plane thereof for engagement upon the rein to retain the plate in an adjusted position.

2. A device of the character described comprising a plate having a toothed outer edge and an opening therein adapted to receive a rein, and spaced clamping plates projecting from opposite sides of the disk and adapted for clamping engagement upon the

- opposite sides of the rein to retain the toothed plate in an adjusted position.
3. A device of the character described comprising a disk having spur teeth on its perimeter and provided with a diametrically extending opening to receive a rein, and plates extending through the opening and secured to the opposite longitudinal edges thereof, the end portions of said plates projecting in parallel relation from the opposite side faces of the disk and in a plane at right angles thereto for clamping engagement upon the opposite sides of the rein to retain said disk in an adjusted position.
- 10 4. A rein spur consisting of a flat plate having pricking teeth on its outer edge, and means fixed to the plate and projecting from one side thereof for attaching the plate to a rein.

5. A rein spur consisting of a flat disk 20 having pricking teeth formed upon its perimeter, and attaching means for the disk including spaced plates fixed to the disk and projecting from one side thereof for engagement against the opposite faces of a 25 rein.

6. A rein spur consisting of a flat disk having pricking teeth formed upon its perimeter, and attaching means for the disk including means fixed to the disk and projecting from opposite sides thereof for 30 clamping engagement with a rein.

In testimony whereof I hereunto affix my signature in the presence of two witnesses.

BENNETT E. JORDAN.
